UNITED STATES PATENT OFFICE.

MANLY PHILLIPS, OF CINCINNATI, OHIO.

EDGE-BINDING ATTACHMENT.

Application filed May 24, 1923. Serial No. 641,244.

To all whom it may concern:

Be it known that I, MANLY PHILLIPS, a citizen of the United States, residing at Cincinnati, in the county of Hamilton and State of Ohio, have invented new and useful Improvements in Edge-Binding Attachments, of which the following in a specification.

My invention relates to attachments for sewing machines used for applying tape or the like to the edges of materials, for protecting such edges or enhancing the appearance thereof. An object of my improvement is to apply the tape with an edge turned under, concealing the selvedge, entirely by sewing, rapidly and accurately; and especially to apply tape in this manner to the edges of the leather upper parts of footwear, whereby an acceptable substitute for the so called French binding is produced. A further object is to provide for ready control of the width of the undeturned part of the tape, and for adjustment to apply tapes of different widths, in conjunction with now widely used sewing machines and their taping attachments. Other objects will appear in the course of the ensuing description.

I attain these objects by the device illustrated in the accompanying drawing, in which—

Figure 1 is a perspective view of part of a sewing machine with the device in operative position thereon;

Fig. 2 is a detail plan view of the intermediate guide, the attaching screws therefor being shown in section;

Fig. 3 is a front view of this guide;

Fig. 4 is a left end view thereof;

Fig. 5 is a right end view thereof;

Fig. 6 is a lengthwise section on the plane of the line 6—6 of Fig. 2, the screws being omitted from this view;

Fig. 7 is a fragmentary enlarged perspective view corresponding to Fig. 1, showing the operation of the device; and

Fig. 8 is a partial left end elevation corresponding to Fig. 7, with the part of the tape emerging from the terminal guide broken away and represented in dotted outline only, better to disclose the terminal guide.

The sewing machine illustrated is of well known construction, comprising the generally cylindrical base arm 1 containing at its end the shuttle, not shown, and the lower

part 2 of the feeding mechanism, to operate in conjunction with the upper part of this mechanism comprising the foot 3 having a four-way motion and the boot 4 having an up-and-down motion, and the needle 5 passing down and up in a notch 6 in the front of the foot 4; such a sewing machine being known as a walking-foot binding machine.

Also well known, as provided by the manufacturers of the above described machine, is the tape applying attachment comprising the primary guide or tension device made up of a series of upright studs 7 in a plate 8 mounted on top of the arm 1, and the binder which comprises a bar 9 fixed to the plate 8 behind the studs 7 and extending in front of the foot 3 with a notch 10 registering with the notch 6, with the adjacent end of this bar concave to form a channel 11 extending back toward the needle 5, and with a passage 12 through this bar 9, of substantially semi-circular cross-section and in longitudinal alinement with the series of posts or studs 7; the concave side of this passage 12 being inverse to the concavity of the channel 11.

This attachment, as is well known in the art, receives the tape 13 threaded between the studs 7 and passing through the passage 12 with its edges thrown back around the convex rear side of this passage and emerging therefrom and turning sharply back along the channel 11 wherein the tape is thrown around the edge of the leather or other flexible material 14 presented thereto in this channel 11; and this material 14 with this tape 13 so folded around its edge passes through the feeding mechanism of the sewing machine and receives the stitching 15 therethrough by coaction of the needle and shuttle, so that the tape is sewed firmly around the edge of the material, concealing this edge and protecting it.

In the manufacture of fine footwear, especially ladies' and misses' shoes of the recent styles, there is a large use of this edge binding for different parts of the uppers; and, for the neatest effect, the appearance of the selvedge of the binding tape on the finished face of the shoe upper is objectionable. This has resulted in the development of an application of the tape in which the tape is sewed to the material in reverse position and then folded over the seam and around the edge, involving cementing as a part of the operation. By this method the

selvedge and seam are entirely concealed, and this production, known as French binding, is in good demand for the best quality of goods. But the operation is complicated, 5 and requires particular care, especially in the use of the cement to avoid marring the surface of the material therewith, so that footwear so finished is considered unduly expensive by many users, among whom there 10 is a demand for a binding which will have the selvedge concealed and thus approximate the neat appearance of the French binding, but be considerably less expensive.

I provide such a binding by turning the 15 edge of the tape that is to come on the outer face of the shoe part, sufficiently under to be caught by the stitching 15, so that the binding is completely applied in the single operation with the sewing machine. This 20 leaves appearing, along the turned edge, the stitching, which however, can be so finely and evenly done that it is not conspicuous, so that a very good imitation of and substitute for the French binding is afforded, 25 and which has been found fully acceptable to the trade before mentioned.

In the above described assemblage of parts of the taping attachment, the binder is spaced a considerable distance toward the 30 needle from the primary guide or tension device; and I interpose between these the intermediate guide 16. The spacing thus provided is necessary, in the ordinary use of the device, to permit the easy travel of 35 the tape from its unfolded condition in the tension device to the semi-circular fold in the binder. My intermediate guide 16 comprises the right-hand mouth 17 flaring upwardly and having its cross-section tilted 40 forwardly (Fig. 5). This mouth leads to the exit 18 at the left end, which is a channel about as wide as the tape thickness, opening backward. In so leading to this channel exit 18, the mouth 17 merges gradually from its more upright posture down to the horizontal posture of the exit, which 45 has its edges very thin as illustrated.

This combination of the mouth 17 and exit 18, gradually changing in posture and 50 reducing in cross-sectional dimensions, permits the tape 13 to be threaded therethrough with its upper edge 19 folded forward in the channel of the exit 18; and when the tape passes into the passage 12 of the binder, 55 the edge 19 is creased down over the front of the remainder of the width of the tape, so that when the tape emerges from the binder and turns sharply toward the needle to be inversely folded around the edge of 60 the material 14, this folded-over edge 19 becomes an underfolded edge concealed under that part of the tape lying on top of the material and lying within the area receiving the stitching 15.

65 In effecting this change in disposition of

the material from the tension device to the creaser, the passage of the tape to the semi-circularly folded condition in the passage 12 is disturbed so that there is a tendency for the tape to ride up in this passage 12 70 and increase the width of edge turning. I provide against this by the tongue 20 extending down from the front of the mouth 17 and coacting with the forwardly convex part 21 of the bar 9, which is a right hand continuation of the rear convex wall of the passage 12 of this bar as the device is constructed by the manufacturers of the machine. This tongue 20 keeps the tape stretched down around this convexity 21 80 from the inception of the edge-turning operation of the mouth 17, so that the tape passes into the passage 12 fully stretched around the curved cross-section thereof, with the width of edge part 19 kept uniform and 85 the opposite unturned edge part 22 of the tape fully extended in across the lower face of the material 14 to receive the stitches 15. It will be understood that this opposite side of the material is concealed, being against 90 some other part of the shoe, such as another upper part or the lining, after the shoe is further assembled.

The bars 9 of the attachments are made with passages 12 of different dimensions for 95 tapes of different widths; and in selecting a bar 9 for use in my invention, allowance is made for the dimension of edge portion 19 to be turned under; so that the tape, with this edge 19 thrown forward, completely fills the semi-circular cross-section of the passage 12 and thus is guided therein with the same facility and accuracy as is a narrower unfolded tape likewise filling the passage. 105

My intermediate guide preferably is made from a single piece of sheet metal, the larger portion 23 of which is the support for the mouth 17, exit 18 and tongue 20, formed from a left-hand forward projection 24 of 110 this portion 23, which latter has two holes 25 and rests on top of the rear part of the bar 9 where this bar is attached to the plate 8, with the screws 26 used to attach the bar 9 through these holes 25 and thus attaching both the bar 9 and my intermediate guide to the machine. As shown in Fig. 2, the holes are amply larger than the screws, so that my intermediate guide can be moved considerably in any direction before final tightening of the screws, which preferably have a washer plate 27 under their heads, wider than the holes 25 and thus insuring ample clamping area at any of these adjustments thus provided. The intermediate guide is adjusted forward or backward, accordingly as a greater or less width of edge portion 19 is to be turned, and adjusted to left or right in accordance with the requirement for keeping the tape fully extended in 130

the passage 12 by the tongue 20 and convexity 21 before described, whether this operation be affected by the change in width of edge-turn, or by variation in the width of tape, or its texture, or degree of tension used. It will be understood that more or less tension is provided in these machines by causing the tape to pass around a greater or less number of the studs 7 in alternate directions, as indicated in Fig. 7. With the interchange of binders as in the usual operation of the machine, and the just described adjustments of my intermediate guide, it thus is possible to produce any width of finished binding desired, uniformly and as rapidly as the machine is usually operated.

Modifications may occur, and while certain details are deemed preferable in connection with my invention, and I have shown and described these rather specifically in elucidating the construction and use of my invention, as is required. I do not wish to be understood as being limited to such precise showing and description, but having thus fully described my invention.

What I claim as new and desire to secure by Letters Patent is:

1. In combination with means for continuously securing tape along an edge of a material, folded around said edge, and a

binder guiding said tape to said edge in the folded condition, having a longitudinal passage of curved cross-section with the convex wall of the passage extending past its entrance a guide having an exit channel with its terminal opening toward said binder and its open side toward said convex wall, receiving and turning one edge portion of the tape passing into the binder, whereby the binder delivers the tape around the edge of the material with said tape edge folded under adjacent to the material, said guide having a tongue projected opposite said convex wall to spread the tape around said wall and throughout the curved cross-section of said passage.

2. In combination with means for continuously securing tape along an edge of a material, folded around said edge, and a binder guiding said tape to said edge in the folded condition, a guide having an exit channel with its terminal opening toward said binder, receiving and turning one edge portion of the tape passing into the binder, whereby the binder delivers the tape around the edge of the material with said tape edge folded under adjacent to the material, said guide being adjustable across and toward the entrance to said binder to vary the width of the turned edge portion of the tape.

MANLY PHILLIPS.
